Primary Examiner — Holly H Baynham*Assistant Examiner* — Rashida C. Walshon(74) *Attorney, Agent, or Firm* — Schrantz Law Firm, PLLC; Stephen D. Schrantz(57) **CLAIM**

The ornamental design for a temperature management device, as shown and described.

DESCRIPTION

FIG. 1 is a partial front environmental view showing my new design;

FIG. 2 is a rear environmental view showing my new design;

FIG. 3 is a front view showing my new design;

FIG. 4 is a top view thereof;

FIG. 5 is a bottom view thereof;

FIG. 6 is a rear view thereof;

FIG. 7 is a left side view thereof; and,

FIG. 8 is a right side view thereof.

The broken lines in FIGS. 1 and 2 illustrate unclaimed environment. Portions of the article in broken lines in FIGS. 3-8 are unclaimed subject matter and form no part thereof. The broken away symbols in the drawings indicate that any portion of the article beyond what is shown forms no part of the claimed design.
